UNITED STATES PATENT OFFICE.

CHARLES W. BUTTS, OF SAG HARBOR, NEW YORK, ASSIGNOR TO JOSEPH FAHYS & COMPANY, OF NEW YORK, N. Y., A CORPORATION OF NEW YORK.

WATCHCASE BOW AND PENDANT.

1,084,253.

Specification of Letters Patent.

Patented Jan. 13, 1914.

Application filed May 1, 1913. Serial No. 764,806.

To all whom it may concern:

Be it known that I, CHARLES W. BUTTS, a citizen of the United States, and a resident of Sag Harbor, county of Suffolk, and State 5 of New York, have invented certain new and useful Improvements in Watchcase Bows and Pendants, of which the following is a full and clear specification.

My invention relates to the manufacture 10 of watch case bows and pendants and involves more particularly the attachment or connection of the bow to the pendant.

The invention is applicable to articles 15 of this character whether formed of solid, precious or other metal, or precious metal filled with base metal.

It is further more especially concerned with the attachment of Swiss or French bows to the pendant.

20 An important object of the invention is to provide an improved connection between the bow and pendant, which is neat in appearance and of great strength and firmness while not interfering with the free 25 movement of the bow on its axis.

The invention also has for one of its objects to provide an improved connection more especially for Swiss bows of filled stock.

30 To illustrate the invention I shall refer to an embodiment thereof with relation to a Swiss bow of filled stock. Swiss bows of filled stock may be produced in various ways and my present invention does not depend 35 upon any one particular method of constructing the Swiss bows, but I may refer to Swiss bows such as those produced according to the U. S. patents to Harman, No. 1,019,636, and Butts No. 1,038,845. A Swiss

40 bow of filled stock similar to those shown in the patents referred to is illustrated in the accompanying drawing as an example of the kind of bow to which my invention is applicable.

45 In said drawing, Figure 1 is a side elevation with a part of one of the bars in section showing a Swiss bow constructed in accordance with my invention; Fig. 2 is a detail sectional view showing the bar provided with the tapered recess for receiving the securing pin; Fig. 3 is a similar view of the bar and part of the pendant, with the securing pin inserted; Fig. 4 is a similar view with the pin permanently secured by 50 the material of the outer end of the bar;

Fig. 5 is an enlarged detail view part in section showing a wire of filled stock after a preliminary operation upon it for forming the securing pin.

As shown in Fig. 1 the Swiss bow comprises the bow portion 10 having bars 11 which are in alinement with each other. The Swiss bow herein shown is constructed of filled stock and the first operation to which the bow is subjected, according to my 60 present invention, is to provide the bars 11 with longitudinal and inwardly tapering perforations, as indicated at 12, to receive the tapered securing pins 13. The bow having its bars thus provided with longitudinal 65 tapered perforations 12 is then fitted onto the pendant 14, which is provided with a head portion 15 in which are formed sockets to receive the inner ends of bars 11, and recesses forming continuations of the per- 70 forations in the bars 11 to receive the tapered securing pins 13. Pins 13 may then be driven inwardly through bars 11 and into the perforations in the pendant head 15, whereby the bow is securely connected with 75 the pendant. The pins 13 are constructed of a wire, as shown in Fig. 5, by first spinning in circumferential depressions 16, whereby the precious metal shell 17 is partly drawn over the base metal which is to form the ends 80 of the pins, and whereby the pin is more or less pointed at one end which is to form the inner end of the pin when the latter is in place within the bow and pendant. The pins are then severed. 85

The small ends of pins 13 have sufficient freedom in the pendant head 15 to turn therein thus forming an axis of oscillation for the bow 10, but are intended to be fixedly secured in the bars 11, which purpose is fur- 90 thered by the tapering form of the pins and perforations. The outer ends of the bars are next subjected to a burnishing operation for crowding inward the material at the outer ends of the bars, whereby the hole in 100 the end of the bar is closed, and the precious metal is worked partly over the outer ends of pins 13. The material of the bars under this last operation is forced into a compact solid mass around the ends of the pins, and 105 the precious metal of the pins is further burnished over the base metal at the outer ends of the pins, as illustrated in Fig. 3.

I have referred to the pins 13 as having been constructed of filled stock, but it will 110

be apparent that the invention is not limited to this specific feature as other forms of pins may be employed.

I claim:

- 5 1. The combination with a pendant provided with sockets and recesses leading therefrom, and a bow having bars seated in said sockets and provided with longitudinal recesses; of securing pins disposed within the recesses of said pendant and bars, with the material of the bars contracted over the outer ends of said securing pins.
- 10

2. The combination with a pendant and a Swiss bow of filled stock mounted thereon; of a securing pin therefor, permanently secured within the pendant and bow, with the precious metal of the outer ends of the bars contracted over the outer ends of the securing pins.

CHARLES W. BUTTS.
